ANTONE ALVA BOWEN AND ROBERT M. PETTUS, OF FRESNO, CALIFORNIA.

SANITARY TOILET.

1,236,902.

Specification of Letters Patent. Patented Aug. 14, 1917.

Application filed April 4, 1917. Serial No. 159,765.

To all whom it may concern:

Be it known that we, ANTONE A. BOWEN and ROBERT M. PETTUS, citizens of the United States, residing at Fresno, in the county of Fresno and State of California, have invented certain new and useful Improvements in Sanitary Toilets, of which the following is a specification.

Our invention relates to the class of toilets.

The object of the invention is hygienic, a result reached through a sanitary measure applied to the toilet seat, whereby said seat is maintained in a condition conducive to health.

To this end our invention consists in the novel toilet which we shall hereinafter fully describe and illustrate in the accompanying drawings, it being understood that both description and drawings disclose the invention in its preferred form, though changes and alterations may be made within the scope of the claims appended, without departing from the spirit of the invention.

In the drawings—
Figure 1 is a side elevation, partly in section, of the toilet.

Fig. 2 is a top plan of the same.

Fig. 3 is a longitudinal section, enlarged, of the seat and its adjacent connections for supplying a liquid disinfectant, the section of the seat and hinge being on the line 3—3 of Fig. 4.

Fig. 4 is a broken top plan view of Fig. 3.

1 is the bowl of the toilet, and 2 is its seat.

To avoid confusion the usual lid is omitted.

3 is the water-flushing tank, communicating with the bowl through a connection 4. The communication is controlled by a valve 5 adapted to be lifted by its stem 6 connected with a rock shaft 7 operated by an exterior handle 8. Water is supplied to the tank from a pipe 9 having a cut off cock at 10. The pipe 9 is automatically controlled by a

45 valve 11 operated by a float 12. All these parts constitute a common standard form of toilet and are intended to represent and stand for any toilet. Their special construction and arrangement, are not, however, essential, it being understood that our invention as hereinafter pointed out is applicable to any form or construction or arrangement 50 of water-flushed toilet.

According to our invention, the seat 2 has fitted to it, or is provided or formed with a 55 perforated encircling fluid conduit in such position that it is adapted to deliver a liquid along the outer border of its upper surface or face, so that said liquid will flow inwardly over and cover and wet the inward sloping 60 face of the seat, the surplus thus flowing into the bowl.

The specific construction and disposition of this fluid conduit may be varied; but, for illustration, we show and prefer a form of 65 seat 2, made of suitable material, say, for example, aluminum, having in its upper portion near its outer border a conduit 13 provided with perforations 14 adapted to deliver the liquid contents of the conduit upon 70 the upper face of the seat, all around its circumference.

In order to supply the seat with liquid we provide a second tank 15, which in practice may be, as here shown, a compartment of 75 the water flushing tank 3. This compartment 15 has a discharge connection 16, which is controlled by a gravity valve 17 the stem 18 of which is connected with the rock shaft 8 of the water flushing tank, in such relation 80 that the water flushing of the bowl, due to the operation of the rock shaft is simultaneous with the discharge of the liquid from the compartment 15 to the seat 2.

The discharge connection 16 from the 85 compartment 15 communicates with the conduit 13 of the seat 2 through the seat hinge, which hinge is of a character to permit the passage of the liquid, while still permitting the usual hinge movement of the seat to lift 90 and lower it, as is common.

This hinge is, also, a valve to control the flow, said valve being open, only when the seat is down on the bowl, but closed when the seat is raised, thereby permitting the 95 water-flushing of the bowl when the seat is elevated, without delivering any liquid from the supplementary tank or compartment 15, and thereby avoiding waste of said liquid, the small amount remaining in the conduit 100 13 and tending to flow out through the lower perforations thereof being negligible. This valve-hinge may be of any suitable character. A good form is that here shown, particular reference being had to Figs. 3 and 4. 105 A pair of arms 19 extend rearwardly from

the back of the seat, and are pivotally mounted on a cross bolt 20, carried by a block 21, which seat is itself carried by the stem 22 of the discharge connection 16 from 5 the supplementary tank or compartment 15.

In the back of the block 21 is made a passage 23 from end to end, with which the passage through the stem 22 of the connection 16 communicates. In each end of the 10 block 21 is made an arcuate port 24. With the rear end of each port 24, the passage 23 communicates permanently. In each seat arm 19 is made a passage 25, the rear end of each passage 25 registering with the forward 15 end of the arcuate port 24, when the seat is down in its normal position on the bowl, but moving out of registry therewith when the seat is lifted from the horizontal. The forward end of each arm passage 25 20 communicates with the conduit 13 in the seat. In Fig. 3, we have shown a screw plug 26, the adjustment of which controls the passage through the connection 16, whereby the rate of flow of liquid supplied may be 25 initially determined and regulated.

The operation of the toilet is as follows:— Any suitable liquid disinfectant is supplied to the supplementary tank or compartment 15. In using the term disinfectant we mean 30 to include any substance used to destroy or restrain the germs or micro-organisms of infectious diseases, whether it acts as a germicide proper, or as an antiseptic to destroy the growth of such micro-organisms of 35 putrefactive nature.

When the rock shaft 8 is moved, in order to water-flush the bowl, the same movement opens the discharge connection 16, and the liquid-disinfectant from compartment 15, 40 flows into the conduit 13 of the seat 2, and is discharged from its perforations 14, over the entire upper face of said seat, the surplus flowing into the bowl. Thus the seat is purified from infection and kept wholesome 45 and free from contamination, and to the extent that the disinfectant flows into the bowl a beneficial result is also had. The disinfectant rapidly dries off so as not to interfere with the comfortable re-use of the seat. 50 The flow of the liquid disinfectant stops, with the release of the rock-shaft handle 8, being controlled by the gravity valve 17, but each time the bowl is flushed, the disinfectant flows to the seat.

55 This is the normal operation of the toilet, assuming the seat to be down on the bowl; but, as heretofore pointed out, if the seat be elevated, as when using the toilet as a urinal, the bowl may still be water-flushed, 60 while the seat is raised, but without having a flow of the disinfectant through the valve hinge which is then closed. This avoids any mistake, and the consequent waste of the disinfectant.

65 Also by properly adjusting the regulating

70 plug 26, the rate of flow of disinfectant is determined so that an unintentionally prolonged holding open of the gravity valve 17 will not result in draining the supplementary tank.

We claim:—

75 1. A toilet comprising a bowl; a seat for the bowl having a perforated fluid conduit encircling its outer border in position to deliver its contents over the upper face of the seat; a hinge connection adapting the seat to be lifted and lowered, said hinge having a passageway through it communicating with the conduit of the seat; a double compartment tank for liquids; a valve controlled connection between one of said compartments and the bowl, through which the bowl may be water-flushed from said compartment; a valve controlled connection between the other tank compartment and the passageway of 80 the seat hinge whereby the seat conduit may be supplied with a liquid disinfectant; and a rock-shaft common to and associated with both said valve-controlled connections for opening and closing them in unison. 85

90 2. A toilet comprising a bowl; a seat for the bowl, having a perforated fluid conduit encircling its outer border in position to deliver its contents over the upper face of the seat; a valve-hinge connection adapting the 95 seat to be lifted and lowered, said connection being open when the seat is down on the bowl, and closed when the seat is lifted therefrom; and controllable means for supplying said conduit with liquid disinfectant 100 through the valve hinge connection of the seat when said seat is down on the bowl.

105 3. A toilet comprising a bowl; means for water-flushing said bowl; a seat for the bowl having a perforated fluid conduit encircling 110 its outer border in position to deliver its contents over the upper face of the seat; a valve-hinge connection adapting the seat to be lifted and lowered, said connection being open when the seat is down on the bowl and closed when the seat is lifted therefrom; means for controlling the water flushing; controllable means for supplying the seat conduit with liquid disinfectant through the valve-hinge connection of the seat when said 115 seat is down on the bowl; and means common to both controlling means for operating them in unison.

120 4. A toilet comprising a bowl; means for water flushing said bowl; a seat for the bowl having a perforated fluid conduit encircling 125 its outer border in position to deliver its contents over the upper face of the seat; a valve-hinge connection adapting the seat to be lifted and lowered, said connection being open when the seat is down on the bowl and closed when the seat is lifted therefrom; means for controlling the water flushing; controllable means for supplying the seat conduit with liquid disinfectant through the 130

valve-hinge connection of the seat when said seat is down on the bowl; means common to both controlling means for operating them in unison; and means for initially regulating the rate of flow of liquid disinfectant supplied the seat conduit.

In testimony whereof we have signed our

names to this specification in the presence of two subscribing witnesses.
